UNITED STATES PATENT OFFICE.

GEORGE B. SHELLHORN, OF MONTGOMERY, ALABAMA.

DESIGN FOR A RUG-FASTENER.

SPECIFICATION forming part of Design No. 22,288, dated March 14, 1893.

Application filed January 28, 1893. Serial No. 460,161. Term of patent 14 years.

To all whom it may concern:

Be it known that I, GEORGE B. SHELLHORN, a citizen of the United States, residing at Montgomery, in the county of Montgomery and State of Alabama, have invented and produced a new and original Design for Rug-Fasteners, of which the following is a specification, reference being had to the accompanying drawing, forming part thereof.

The drawing forming part hereof shows my newly designed fastener in perspective.

The leading feature of my design consists in the triangularly shaped body having concave edges and tapering extensions projecting at right angles from the body at its angles; one of said extensions projecting oppositely to the other two.

A is the flat triangular body; *d* the concavities in the edges thereof; *b b* two tapering extensions projecting in the same direction from two angles of the body and *c' c* is a similar tapering extension on the remaining angle and projecting oppositely to the extensions *b b*. 20

Having thus described my invention, what I claim is—

The design for a rug fastener herein shown and described. 25

GEORGE B. SHELLHORN.
